To all whom it may concern:

Be it known that I, Samuel N. The figure is a front view of an athletic shirt or similar garment showing my new design. The back of the garment corresponds to the front.

The dominant feature of my design resides in the specific combination on the athletic shirt or similar article, as shown, of the V-shaped insert between the shoulder portions, said shoulder portions contrasting to the body portion.

I claim:—

The ornamental design for an athletic shirt or similar article, substantially as shown and described.
